(57) **CLAIM**

The ornamental design for a level sensing switch, as shown and described.

DESCRIPTION

FIG. 1 is a perspective view of a first embodiment of a level sensing switch showing our new design.

FIG. 2 is a top view thereof.

FIG. 3 is a bottom view thereof.

FIG. 4 is a left side view thereof.

FIG. 5 is a right side view thereof.

FIG. 6 is a front view thereof.

FIG. 7 is a rear view thereof.

FIG. 8 is a perspective view of a second embodiment of a level sensing switch showing our new design.

FIG. 9 is a top view thereof.

FIG. 10 is a bottom view thereof.

FIG. 11 is a left side view thereof.

FIG. 12 is a right side view thereof.

FIG. 13 is a front view thereof; and,

FIG. 14 is a rear view thereof.
